UNITED STATES PATENT OFFICE.

HENRY F. GRAY, OF COLUMBUS, OHIO, ASSIGNOR OF ONE-HALF OF HIS
RIGHT TO ALBERT D. FIELD, OF SAME PLACE.

WINDOW-CORNICE.

SPECIFICATION forming part of Letters Patent No. 228,189, dated June 1, 1880.

Application filed March 17, 1880. (No model.)

To all whom it may concern:

Be it known that I, HENRY F. GRAY, of Columbus, in the county of Franklin and State of Ohio, have invented a new and useful Improvement in Window-Cornices, of which the following is a specification.

The invention relates to inside and adjustable cornices; and it consists of a right-and-left-hand screw-rod, in combination with adjustable arms and other devices, all of which will be understood by the accompanying drawings and description.

In the accompanying drawings, Figure 1 is a front view of my cornice. Fig. 2 is a back view of the same. Fig. 3 is a top view.

In the construction of my cornice the two arms *a a* are arranged to slide in grooves *d d*, being moved by means of the right-and-left-hand screw-rod *e*, working in nuts or ears *b b* 20 between the stops *c c*, attached to the center-

piece *h h*. By this construction the arms *a a* may be easily adjusted to suit the width of different windows without changing the general appearance of the cornice.

I do not broadly claim an adjustable cornice; but I believe the above-described construction of cornice is new, and it is very convenient and useful.

Having described my invention, what I claim is—

The above-described window-cornice having the center-piece *h h*, in combination with the adjustable arms *a a*, sliding in grooves, and adjusted by means of the right-and-left-hand screw-rod *e*, substantially as and for the purposes set forth.

HENRY F. GRAY.
